UNITED STATES PATENT OFFICE.

EDWARD J. TOMLINSON, OF NEWARK, NEW JERSEY, ASSIGNOR TO SPLITDORF ELECTRICAL COMPANY, OF NEWARK, NEW JERSEY.

PHONOGRAPH.

Application filed January 8, 1920. Serial No. 350,219.

To all whom it may concern:

Be it known that I, EDWARD J. TOMLINSON, a citizen of the United States, residing at Newark, in the county of Essex, State 5 of New Jersey, have invented certain new and useful Improvements in Phonographs, of which the following is a description, reference being had to the accompanying drawing and to the figures of reference marked 10 thereon.

This invention relates to electrically operated phonographs and as illustrated is particularly adapted for use in playing a record in the form of a plate or flat disk.

15 It is the principal object of my invention to provide a phonograph in which the sound record body is carried on a rotatable support electrically driven in such a way as to insure a constant and uniform rotative 20 speed as well as giving quietness in operation.

In many types of electrically operated phonographs the torque is not uniform and the tempo of the played record is seriously 25 impaired. It is, therefore, one of the objects of my invention to provide a motor which will give uniform tempo.

Another object of my invention is to provide an electric phonograph motor which is 30 self-starting, that is to say, no, additional starting mechanism is required to give the rotative part carrying the sound record an initial starting impulse as is very common in phonograph motors.

35 Another object of my invention is to provide a phonograph motor which aside from being self starting will come up to its normal running speed within a very brief interval of time, so that, in the usual method 40 of placing the needle on the record, the motor has attained its normal running speed before the needle has reached the playing portion of the record.

Another object of my invention is to provide a phonograph motor which is neat and compact and of rigid construction, all of 45 which tends to produce long life of the instrument.

Other and further objects of my invention 50 will be apparent to one skilled in the art.

after a study of the specification taken in connection with the annexed drawings which constitutes a part thereof, wherein—

Figure 1 is a top plan view of the motor itself without the mounting plate. 55

Figure 2 is a bottom plan view of the motor showing the same carried by a mounting plate suitable to go into the usual cabinet.

Figure 3 is a side elevation of the motor in the mounting plate with a portion of the sound record body and support shown in section. 60

Figure 4 is a top view of Figure 1 on a smaller scale but with the two cover plates removed and the rotatable member withdrawn. 65

Figure 5 is a section along the line 5—5 of Fig. 1.

Figure 6 shows a plan view of the rotatable member. 70

Figure 7 is a view on the line 7—7 of Fig. 6 with the armature and field windings removed for the sake of clearness.

Figure 8 illustrates diagrammatically one 75 method of connecting the mechanism of the motor.

Figure 9 shows another method of wiring the motor.

Figure 10 shows a still further modification of internal connections. 80

Referring now to the details wherein like numbers refer to corresponding parts in the various views, 1 illustrates a cup-shaped casing from which extends the pocket. 2. 85 The casing 1 has lugs 3 with holes 4 therein by which the casing is carried on a frame or mounting plate 5 by means of suitable screws 6 and bushings 7 preferably of soft rubber whereby any small vibrations in the motor itself are deadened in their course of transmission to the mounting plate 5. Carried within the cup-shaped casing 1 is a magnetic element 8 having a series of poles 9 and preferably laminated, about which are placed windings or field coils 10. 90

The member 8 is fastened to the central portion of the cup-shaped member 12 in any suitable manner such as by screws 11. 95

The central portion of the member 1 car- 100

ries a bearing which may take the form of a screw 70 having a rounded and hardened point or the end of the screw may adjustably carry in position a hardened ball. As shown 5 in Figures 2 and 5 the screw is locked in adjusted position by the nut 13. Also carried by member 1 and within the member 8 and centrally located around the member 12 is a brush holder ring 14 carrying brush hold- 10 ers 15 and brushes 16. The ring 14 can be rotatably adjusted by means of the slots 45 and screws 46. The brushes are adapted to engage the bars of the commutator 17, the line of the commutator being indicated 15 by the dotted lines 18, Figure 4. The commutator 17 is carried on and fastened to hub 19 in any suitable manner as by screw 32. The hub 19 is preferably integral with the bottom of the rotatable casing 20 which has 20 a flange 21 that carries a magnetic element 22, the same being fastened to the flange in any suitable manner such as by screws 23. The magnetic element 22 is preferably laminated and constructed with a series of slots 25 24 forming pole teeth 25. Located within the slots 24 is preferably a series of coils 26, the number of which is a multiple of the field poles 9, plus or minus one, the field poles being of an even number. The coils 30 26 are connected to the commutator by suitable leads 27 that are fastened to an insulating member 28 in any suitable manner such as by shellac or varnish, a short commutator riser 29 being used to fasten the leads 27 35 to the proper bars of the commutator 17. To the central hub 19 is fastened a shaft 30 as by means of a key 31. The end 33 of shaft 30 is adapted to run on the bearing 70 and is therefore preferably hardened and ground 40 to a smooth surface. The outer end 34 of shaft 30 is adapted to receive the sound record support body 35 that carries a sound record 36.

The casing 20 with all of the parts assembled therein as just described, and illustrated in Figures 6 and 7, is adapted to fit within the cup-shaped casing 1 and to rotate therein and after the said casing 20 with its parts has been put in a position 45 whereby the pole teeth 25 are in operative relation with poles 9 and the brushes 16 are in the commutator 17, then the cover plate 17 carrying a guide bearing 38 is put in place and fastened by means of the screws 40 entering the screw holes 40 in the casing 1. A small cover plate 41 is adapted to fit over the pocket 2 as well as around the cover 37 on the line 42. From this construction, shown particularly in Figures 1 50 and 5, it is seen that the moving parts of the motor are completely concealed and are protected from dust, dirt and mechanical injury. Within the pocket 2 is carried a governor mechanism broadly indicated by the 55 numeral 43. The particular governor mech-

anism illustrated herein will be made the subject of a separate application and will not be described in detail herein. The governor shaft is operated by a suitable drive member 69 which engages a knurl 44 that is 70 turned on the edge of the flange 21.

The frame or mounting plate 5 carries a block 47 preferably of insulating material on which is mounted an electro-magnetic coil 48 to the core of which is attached pole pieces 49 and 50. One of these pole pieces, such as 49, carries a movable armature 51, which is normally held in retracted position by means of a spring, such as 52. The mounting plate 5 also supports a switch lever 53, one end of which carries a contact piece 54 that is insulated from the lever 53, but adapted to make electrical connection between the switch blades 55 and 56, as illustrated diagrammatically in Figure 8, 80 whereby a circuit through the motor is completed, as will be seen. The upper end of the lever 53 carries a brake shoe 57 constructed of any suitable material and is adapted to engage the sound record support body 35. The lower end of the lever 53 carries a detent 58 which engages the end of the armature 51 so that the lever 53 cannot return to its normal position, after being operated, until the armature 51 has been 90 withdrawn. This withdrawal of the armature 51 may be accomplished in two ways; first, automatically by the tone arm 59 engaging a contact 60, as described in my co-pending application S. N. 333,800, filed October 27, 1919, whereby a circuit through the electromagnet 48 is completed (see Figure 8), and the armature 51 drawn up thereby allowing the spring 61 (see Figure 2), to turn the switch lever 53 to the position shown in Figure 3, and thereby move the brake shoe 57 into engagement with the member 35, stopping the phonograph. If it is desired to stop the phonograph motor 100 at any other time this may be done by means of a push button 62 which in turn will operate the member having a cam surface 63, in such a way that this will push the armature 51 out of engagement with the detent 58, allowing spring 61 to return the lever 53 to a position as previously described.

As indicated in Figure 8 the winding 26 is illustrated by the motor armature 26 and the field windings 10 are shown connected in series. For the purpose of regulation, the action of resistance 64 is controlled by the governor 43 in accordance with the speed of rotation of the governor. Connections to the motor are made from the terminals 65, 66 and 67. As illustrated in Figure 9 a relay 68 is adapted to cut in or out of the motor circuit a portion of the resistance 64 at the proper time, whereby the governor 43 switches in or out of the motor circuit more or less resistance, according to the position 110 120 125 130

of the relay 68. As indicated in Figure 10 the field winding 10 is shunted by the resistance 64 and the governor 43 controls a part of the said shunt resistance.

5 It should be noted that the arrangement of the coils and the ratio of the number of poles in the pole pieces insures a positive starting of the armature from any stationary position of the armature, as well as 10 insures a quiet operation of the motor during its running.

Other schemes of internal connections will be clearly apparent to one skilled in the art and I do not wish to be limited to the 15 manner of connections as illustrated. It will also be apparent that numerous changes can be made in the details of the various parts without departing from the spirit of my invention and the scope of the appended 20 claims.

Having thus described my invention, what I claim is:—

1. A phonograph driving mechanism comprising in combination, a casing opening upward and having a bearing in the bottom thereof, a cover to close the casing opening and carrying a guide bearing, a magnetic field structure supported within said casing and having a plurality of poles with exciting windings thereon, a rotatable member having a shaft, one end cooperating with the bearing in said casing and the other end extending through the cover guide bearing and adapted to receive a sound record support body, said rotatable member further consisting of; a cup-shaped body fitting within said casing and having a central portion fastened to said shaft, a magnetic element fastened to the said cup-shaped body, said magnetic element having slots forming pole teeth therebetween arranged in its inner periphery and a series of armature coils arranged in said slots so as to embrace a plurality of said pole teeth, a commutator for said armature coils carried on said central portion, means for applying current to said windings and coils, and means for governing the speed of rotation of the rotatable member.

50 2. A phonograph driving mechanism comprising in combination, a casing opening upward and having a bearing centrally located in the bottom thereof, a cover to close the casing opening and carrying a guide bearing, a magnetic field structure supported from the bottom of said casing and having a plurality of outwardly extending pole pieces with exciting windings thereon, a brush holder with commutator brushes carried thereon supported by the bottom of said casing within said field structure, a rotatable member consisting of a cup-shaped body fitting within said casing and carrying an armature ring having slots forming inwardly projecting pole teeth to cooperate with said

field poles with overlapping coils disposed in said slots, said cup-shaped body having a central portion forming a seat for a commutator connected to said armature coils and cooperating with said brushes and a shaft 70 fastened to said central portion, one end of said shaft being journaled in said centrally located bearing and the other end extending through the cover guide bearing and adapted to receive a sound record support body, 75 means for passing current to said first winding and armature coils via the commutator and means for regulating the speed of rotation of the rotatable member.

3. A phonograph driving mechanism comprising in combination, a flat bottomed cup-shaped casing carrying a magnetic field structure on the bottom of the cup spaced between the center and side walls thereof, a plate covering the casing opening and carrying a shaft bearing an armature structure carried by a movable flat topped cup-shaped casing fitting within the first mentioned casing and having a shaft with one end seated in a bearing carried by the first casing, said shaft having one end extending through the bearing in the cover plate and beyond the movable casing and carrying a sound record support body.

4. A phonograph driving mechanism comprising in combination, a cup-shaped casing having a side pocket extending laterally only of the casing, a magnetic field structure carried by said casing, a rotatable cup-shaped member positioned within said casing in an inverted position and having a shaft with one end supported by a bearing carried by said casing and the other end adapted to receive a sound record support body, said rotatable member carrying an armature structure including a commutator therefor and a speed governor device for controlling the speed of said rotatable member positioned in said pocket and operated by said rotatable member.

5. A phonograph driving mechanism comprising in combination, a cup-shaped casing having a side pocket, both opening upward, a bearing centrally located in the bottom of said casing, a circular field ring fastened to the bottom of said cup and having poles with exciting windings thereon, a rotatable cup-shaped member positioned within said casing in an inverted position and having a shaft with one end positioned in said bearing, a plate fitting over and around said rotatable member and having a guide bearing for the other end of said shaft which extends therethrough and adapted to receive a sound record support body, a circular armature structure fastened to the side walls of said rotatable member and having a commutator centrally located around said shaft and a speed governor for controlling the speed of the rotatable member positioned in said

65
pocket and driven from the outer surface of
said rotatable member.

- 66
5 7. A phonograph driving mechanism comprising in combination, two telescopic casings one rotatable within the other and adapted to carry a sound record support body, a magnetic field structure positioned in the stationary casing and a co-acting armature in the rotatable casing, a pocket
10 10 in the stationary casing containing a governor mechanism, a cover plate fastened to the stationary casing covering its opening as well as the rotatable casing and a separate cover plate covering said pocket and said governor mechanism.

- 15 8. A phonograph driving mechanism comprising in combination, a cup-shaped casing having a cover plate with a guide bushing therein and carrying a bearing centrally located in its bottom part and having a side pocket, a second cup-shaped casing telescoping within the first and supported thereon by a shaft having one end positioned in said bearing and the other end extending through the guide bushing and carrying a sound record support body, a magnetic field structure fastened to the bottom of the first casing, an armature structure carried by the second
20 25 30 casing in cooperative relation with said field structure, a governor mechanism positioned in said pocket and operated by the second casing, a cover plate fastened to the first casing and covering the second and carrying a guide bearing and a separate cover plate for said pocket and governor mechanism.

- 35 9. A phonograph driving mechanism comprising in combination, a cup-shaped casing having a cover plate with a guide bushing therein and carrying a bearing centrally located in its bottom part and having a side pocket extending laterally only of the casing, a second cup-shaped casing telescoping within the first and supported thereon by a shaft having one end positioned in said bearing and the other end extending through the guide bushing and carrying a sound record support body, a magnetic field structure fastened to the bottom of the first casing, a brush holder carrying brushes adjustably mounted on the casing within said field structure, an armature structure carried by the second casing and consisting of a commutator extending within the field structure into operative relationship with said brushes and a magnetic element with windings thereon attached to the periphery of the second casing and co-operating with the field structure to produce rotation of the second casing, a governor mechanism positioned in said pocket and operated by the second casing and covering means for the pocket and second casing.

40 10. A self starting phonograph driving

70 75 mechanism comprising in combination, two telescoping casings, a cover plate for the outer casing, one casing supported by the other and the cover plate and rotatable therein and adapted to carry a sound record support body, a magnetic exciting field structure carried by one casing and a co-acting armature structure in the other casing, a mounting plate and lugs on the stationary casing for attaching the same to the mounting plate.

outside of said first named magnetic element and having an odd number of poles in excess of the number of poles on the stationary magnetic element, coils arranged on the poles of odd number so as to embrace more in arcuate length than the length of one of the stationary poles, and a commutator located within said stationary magnetic element for directing current to and from said rotatable coils. 10
 5 In testimony whereof, I affix my signature.

EDWARD J. TOMLINSON.

Certificate of Correction.

It is hereby certified that in Letters Patent No. 1,473,363, granted November 6, 1923, upon the application of Edward J. Tomlinson, of Newark, New Jersey, for an improvement in "Phonographs," an error appears in the printed specification requiring correction as follows:

Page 4, after line 2 insert the following as claim 6:
A phonograph driving mechanism comprising in combination two telescopic casings, an outer stationary one and the other rotatable within the first through the medium of an operating shaft having a bearing in the stationary casing, said shaft being adapted to carry a sound record support body, a magnetic field structure positioned in the outer stationary casing and a coasting armature carried by the inner casing and a flat cover plate fastened to the stationary casing covering its opening as well as the rotatable casing, said plate carrying a guide bushing for the operating shaft.;

and that the said Letters Patent should be read with this correction therein that the same may conform to the record of the case in the Patent Office.

Signed and sealed this 18th day of December, A. D., 1923.

[SEAL.]

KARL FENNING,
Acting Commissioner of Patents.
